UNITED STATES PATENT OFFICE.

BENJAMIN JOACHIM, OF NEWARK, NEW JERSEY.

DESIGN FOR A BADGE OR PIN.

No. 38,158.

Specification for Design.

Patented Aug. 14, 1906.

Application filed June 12, 1906. Serial No. 321,413. Term of patent 7 years.

To all whom it may concern:

Be it known that I, BENJAMIN JOACHIM, a citizen of the United States, residing at Newark, county of Essex, and State of New Jersey, have invented a new, original, and ornamental Design for a Badge or Pin, of which the following is a specification, reference being had to the accompanying drawings, forming part thereof.

I claim—

The ornamental design for badge or pin, as shown.

BENJAMIN JOACHIM.
